UNITED STATES PATENT OFFICE

ROLAND A. FURLONG, OF ROCHESTER, NEW YORK, ASSIGNOR TO THE YAWMAN & ERBE MANUFACTURING COMPANY, OF ROCHESTER, NEW YORK, A CORPORATION OF NEW YORK

MULTIPLE LABEL HOLDER

Application filed June 27, 1930. Serial No. 464,164.

This invention relates to a multiple label holder suitable for use on visible index trays, drawers, and the like, where provision must be made for more than one label holder and 5 also for a finger pull. The principal object of the invention is to provide an improved label holder for the purpose set forth which shall be made of integral construction while adapted for the support of more than one 10 label and may be secured in place partly by a hand pull on the tray or drawer to which it is to be attached and partly by independent securing means such as rivets engaged therewith at other points. More particularly, the 15 invention is concerned with a label holder for visible index trays which shall be suitable for supporting two labels at opposite sides of the hand pull which is disposed centrally of the tray and which label holder shall 20 be of simple and inexpensive construction being formed from a single stamping operation and adapted for convenient attachment to the tray by means of a single rivet engaged therewith adjacent each extremity and the 25 hand pull which is engaged therewith at the mid section.

The construction will be described more particularly in connection with the embodiment illustrated in the accompanying drawings, wherein:

Figure 1 is a view in front elevation of a visible index tray having a hand pull disposed centrally thereof and one of the improved multiple label holders secured thereto.

Figure 2 is a view in plan of a part of the tray shown in Figure 1 and showing the securing means for the label holder in section, parts being broken away for this purpose.

Figure 3 is a view in vertical section through the label holder taken on the plane indicated by the line 3-3 of Figure 1 and looking in the direction of the arrows.

There is illustrated in the drawings the front piece α of a visible index tray but it will

be understood that the improved label holder may be applied to other similar drawers or compartments for other purposes. To the tray α is fastened the improved label holder b . In accordance with the invention this holder is made in a single stamping operation and formed to provide two distinct card receiving portions b' , b^2 , connected by a centrally disposed web b^3 and having at its opposite ends securing flanges b^4 . The label holder is of simple and inexpensive construction and lends itself to ready attachment to the member with which it is to be associated. Thus it appears that rivets c , c' , may pass through the terminal flanges b^4 and engage the tray front α . Such anchorages would not be sufficient without a positive attachment for the central web b^3 . This is afforded in accordance with the invention by the rivet d for the finger pull d' , this rivet d passing through the web b^3 and engaging the tray front α for the joint purpose of retaining the label holder in position and attaching the finger pull to the tray. By reason of the construction and relation of parts resulting therefrom it will be evident that the fewest number of parts possible are required for attachment of the label holder to the member with which it is associated. Two rivets c , c' , are the only special attachment members employed. Further, the resulting disposition of parts is quite attractive and balanced because the finger pull d' lies centrally between the card receiving portions b' , b^2 and no additional attaching means are exposed to view.

It will be appreciated that while the label holder illustrated is adapted to receive only two cards it is conceivable that an equally advantageous device might be made in which some of the advantages are retained and capacity is afforded for more than two labels.

What I claim is:

In combination with a movable member a label holder applied thereto and including a

plurality of spaced label receiving portions and means to secure the label holder to the movable member consisting of single elements passing through the label holder adjacent each end and attached to the movable member and a finger pull for the slideable member passing through the label holder at a point between the card receiving portions and engaged with the movable member.

15 This specification signed this 24th day of
June A. D. 1930.

ROLAND A. FURLONG.
